UNITED STATES PATENT OFFICE.

HENRY PERCY McCOLL, OF MELBOURNE, VICTORIA, AUSTRALIA.

ELECTRIC-SWITCH-ACTUATING MECHANISM.

Application filed August 21, 1922. Serial No. 583,600.

To all whom it may concern:

Be it known that HENRY PERCY McCOLL, a subject of the King of Great Britain, residing at Melbourne, in the State of Victoria, Commonwealth of Australia, has invented certain new and useful Improvements in Electric-Switch-Actuating Mechanism, of which the following is a specification.

10 The present invention has been devised primarily to provide a simplified form of actuating mechanism for a pendant or pull-cord electric switch, but its application is not restricted thereto as the actual member 15 controlled by the hand may be a rod or other mechanical device capable of transmitting motion.

The invention does however refer specifically to switching means which at each successive actuation or impulse effects reverse movement of the switch arm that is to say, if the first actuation effects closure of the switch the next following actuation operates to open the switch.

25 Briefly stated the essential features of this invention comprise a pivoted switch arm actuated in one direction by temporary engagement with a floating draw bar the force of which latter is applied to the arm at a 30 point located at one side of the axis of the arm.

Said floating draw bar follows the movement of the switch arm and when the force applied to the bar is removed it is automatically returned by spring action and positions itself to again temporarily engage with the switch arm but the force applied to the latter at the next operation of the switch is at a point located at the opposite 40 side of the axis of the arm to that operated upon by the previous switch actuation.

The accompanying drawings illustrate a practical form of the invention,

Fig. 1 being a vertical section through 45 the switch actuation mechanism, and

Fig. 2 a similar view showing the draw bar pulled down and held temporarily in such position by hand.

Fig. 3 is an underside plan of Fig. 1 with 50 the cover removed.

Fig. 4 is an enlarged plan and

Fig. 5 a side elevation of the switch arm.

Fig. 6 is an enlarged face view, and

Fig. 7 an edge view of the draw bar.

55 Fig. 8 and Fig. 9 are elevations at right angles to each other of the metal frame of

the mechanism the former figure showing the switch arm in section.

According to these illustrations the pivoted switch arm S consists of duplicate flat 60 pieces 1, 1 joined by transverse pins 2, 3 at equal radial distances from and on opposite sides of the pivotal centre 4 of said arm, and it will be noted that the angle contained between a line drawn from each of said pins 65 to said centre is approximately 135 degrees.

The pieces 1, 1 are mounted on pivots 4, 4 fixed or screwed in the side members 5, 5 of a metal frame F which members 5, 5 are joined at the top and bottom by cylindrical 70 ends 6, 7. The former end 6 has a central opening internally screw threaded as at 8 to engage the external threads of a shouleder hollow screw 9 dropped into a hole 10 formed in the porcelain cylindrical block 11 75 and the end 7 has also a central opening 12 and is externally screwed to engage the cover 27.

The draw bar D is approximately Y-shaped with a central recess 14 and its 80 prongs 15 are formed with hooks 17, 18 with sloping noses 31 and said draw bar is located in the centre of the frame F and slides vertically in a slot 19 of a transverse guide 20 joined to the side members 5, 5 of the 85 frame, said guide having bevelled edges 21.

A spring 22 is connected at one end with the shank 23 of the draw bar and at its other end with the screw 9 as for instance by means 90 of a transverse pin 24 passed through a loop at the top of the spring, said pin being seated in the diagonal notches formed in the top of the screw. To the lower end of the draw bar is attached a pull cord 25 which passes through the opening 12 of the frame F, and a coincident guiding orifice 26 formed in the cover 27 which is screwed on to the end 95 of the frame, and encloses the mechanism.

Connected with one side piece 1 of the switch arm S at the point 28 is the lower 100 end of a spring 29 attached at its upper end to the upper end of the frame, said spring maintaining the switch arm in one or the other of its two positions according to which side of the vertical plane through the pivot 105 4 the lower end of the spring is positioned.

By reference to Figs. 1 and 2 it will be seen that according to whether the switch S is in the closed or open position (in the case 110 of a one way switch as illustrated in full lines in the drawings) one or other of the pins 2, 3 is nearer to the vertical plane

through the pivot of the switch than the other consequent upon the angular relationship of the pins to said plane as illustrated and that one of said pins is always in the path of one of the hooks 17 or 18 of the draw bar D. It is to be noted that said draw bar being loosely suspended by the spring 22 and connected with the cord 25 is free to sway edgewise in the guide slot 19 and is therefore a floating element and as the draw bar is pulled down from the position shown in Fig. 1 the hook 17 engages pin 2. The switch arm is then caused to swing down on its pivot 4 and interrupt the circuit at contacts C and as the hook 17 is in engagement with the pin 2 the draw bar is drawn sideways as in Fig. 2 until spring 29 by reason of its lower end arriving on the opposite side of the vertical centre of the pivot 4 retains the switch arm in the position shown in such figure and the draw bar becomes disengaged from the pin 2 of said switch arm.

During this action the side sway movement of the draw bar permits its other hook 18 to pass pin 3 which is now closer to the vertical plane of the pivot 2 and actually in the path of hook 18 but when the cord 25 is released spring 22 returns the draw bar to normal position and as it moves vertically the sloping nose 31 of hook 18 contacting with the pin 3 causes the draw bar to again move slightly to the right as in Fig. 2 so that hook 18 passes on the inner side of the pin 3 and eventually assumes the equivalent position of the hook 17 in Fig. 1 ready to reverse the switch arm when the cord 25 is again pulled. Thus the alternate pulls on the cord makes and breaks the circuit of contacts C.

It will be appreciated from the foregoing that in the practical application illustrated it is essential to provide means such as the orifice 26 to maintain the correct alignment of the draw bar D.

In the case of a throw-over switch additional contacts C¹ are provided in the

block 11 and an extension arm 30 added to the pieces of the switch arm S as shown in broken lines in Figs. 1, 2, 3, 4 and 5.

Thus the switch alternately makes contact with contacts C and C¹ by successive pulls of cord 25.

It is to be understood that the invention is not restricted to any particular construction of the floating and spring controlled draw bar mentioned nor to the means employed to effect the temporary engagement stated between same and the switch arm as same may be varied to suit varying requirements.

It will be appreciated from the foregoing that in its broadest form the invention may be regarded as combining with a pivoted switch arm a draw bar operating alternately at opposite sides of the axial centre of the switch arm so that successive actuations operate the arm in an opposite direction, the arm being disengaged from the draw bar after the completion of each operating stroke.

I claim:—

1. A pull cord electric switch comprising a pivoted switch arm having a pin on each side of its pivot, a spring fixed to the arm midway between said pins, a draw bar formed at each side with hooks having sloping noses, and means to reciprocate said draw bar and retain it centrally of the switch arm, whereby said hooks alternately engage the pins.

2. In a pull-cord electric switch, a switch arm pivoted within the frame and formed of two side pieces joined by pins located one on each side of the pivot of said arms, a spring connecting the upper end of said arm with the upper end of the frame, a floating draw bar central of the frame and located in a slotted guide therein said bar being suspended by a spring and having a pulling element attached thereto and said bar being formed on each side with a hook having a sloping nose.

Dated this 18th day of July, 1922.

HENRY PERCY McCOLL.
